METAL PUMP FOR TYPOGRAPHICAL MACHINES

Ransom H. Turner, Little Neck, Long Island, N. Y., assignor to Intertype Corporation, Brooklyn, N. Y., a corporation of New York

Application June 14, 1933, Serial No. 675,848
In Germany June 15, 1932

16 Claims. (Cl. 22—70)

The present invention relates to improvements in the metal injecting pump for the metal pot of a line casting machine, and more particularly to that of the well-known class substantially shown and described in U. S. Letters Patents Nos. 436,531 and 436,532, granted September 16, 1890, wherein the pump, actuated by a spring and under the control of a rotary cam, forces a charge of molten metal out of the metal pot into a mold to cast a type bar or slug against a composed line of character bearing matrices, the cam making one complete revolution for each cycle of operation of the machine and having its active surface concentric throughout, except for a recess or depression at one point in its circumference to permit the pump plunger to descend under the action of its spring at the proper time for making the cast. The pump plunger is normally held by the cam in raised or inactive position against the tension of its spring by a pump lever pivoted on the machine frame and carrying a roller on one of its arms which bears against the cam, the other arm of said lever being connected directly to the pump plunger rod, and since the roller, under the tension of the pump actuating spring, rides on the surface of the cam for the greater part of each revolution thereof or during the time the pump is inactive, the surface of the cam in pumps as heretofore generally used, is subjected to considerable wear.

It is desirable, especially for casting large slugs, that the pressure of the pump spring be as great as possible in order that the metal will be injected with sufficient force into the mold, but under such increased pressure the wear of the cam would become excessive unless some means were provided to compensate therefor. Moreover, while returning the pump plunger to inactive or retracted position after a metal injecting or casting stroke, considerable resistance is offered to the rotation of the cam while stretching or resetting the pump spring through contact of the pump roller with the rapidly rising surface of the cam at the end of the recess or depression therein following the pump release point.

The primary object of the present invention is to provide novel means for distributing the load exerted by the pump spring means acting against the pump controlling cam, both while sustaining the pump plunger means in inactive position and while lifting or retracting the pump plunger means after the metal injecting or casting stroke thereof. To accomplish these results, the present invention provides a plurality of rollers for sus-

taining the pump plunger means in inactive or retracted position, these rollers being so arranged that during the lifting or retracting of the pump plunger means, the rollers will successively come into action and each of the rollers will sustain a portion of the load imposed while in the act of stretching the pump spring or springs. The present invention also proposes arranging these rollers so that as the load imposed by stretching the pump spring or springs increases, there will be a compensating increase in the lever arm through which the successive rollers operate in contacting with the rotating cam. The present invention further provides an arrangement whereby the spring pressure for injecting the metal into the mold can be appreciably increased to any extent desirable for producing slugs of large size and, notwithstanding the supporting of the load resulting from such increased spring pressure on a plurality of rollers, all of the rollers will be released simultaneously and thereby render the entire spring pressure acting on the metal pump effective for the metal injecting operation.

According to the present invention, the machine may be provided with a pump having one or several pump plungers, working in the usual metal pot, it being preferable if several pump plungers are used, that each be provided with its own pump spring. The invention however enables but one pump cam to be used, as is usual with machines of this class, the rollers being arranged to run one behind the other on the same cam.

To these and other ends, the invention consists in certain improvements and combinations and arrangements of parts all as will be hereinafter described, the features of novelty being pointed out particularly in the claims at the end of this specification.

In the accompanying drawings:

Figure 1 is a side elevation of the casting mechanism of a line casting machine embodying the present invention;

Figure 2 is a top plan view of part of the mechanism shown in Figure 1;

Figure 3 is a side elevation of the casting mechanism of a line casting machine constructed in accordance with another embodiment of the present invention, the parts being shown in the position they occupy immediately before casting operation.

Figure 4 is a side elevation of a part of the mechanism shown in Figure 3 but showing the parts in the position they occupy when the pump plunger is about to be lifted or retracted; and

Figure 5 is a top plan of part of the structure shown in Figure 3.

Similar parts are designated by the same reference characters in the different figures.

Referring first to Figures 1 and 2 which show the invention applied to casting mechanism wherein the metal pot is provided with a plurality of pump plungers and a corresponding plurality of pump levers and springs, each lever having its roller working against the control cam, 1 represents the metal pot which may be substantially similar in construction to that used generally in line casting machines of the class referred to, it containing a pump comprising a plurality of cylinders 2 and a corresponding plurality of plungers 3 reciprocable vertically therein, the pump cylinders communicating with a throat 4 leading to a mouth piece 5 adapted to be brought against the mold in which the type bar or slug is to be cast in the usual manner and through which the molten metal is injected into the mold by descent of the pump plungers 3. In the present case, three pump plungers are shown, and a corresponding set of three pump levers 6, 7 and 8 are provided, these pump levers being pivoted to rock on a common shaft or pivot 9 supported by a bracket 10 mounted in fixed position on the frame of the machine and one arm of each of these levers is pivotally connected to the actuating rod 11, 12 or 13 of the respective pump plunger, and such arm of each of the pump levers is acted on by a tension spring 14 through a rod 15 so that these springs act to swing the respective pump levers in a direction to force the respective pump plungers downwardly and thereby effect injection of molten metal from the metal pot into the mold. The other arms of the pump levers carry rollers 6^a, 7^a and 8^a, respectively, which are arranged to run, one behind the other on the cam 16 which may be mounted on the main cam shaft 17 as usual in machines of this class, the periphery or active surface of this cam being concentric throughout its extent except for a recess or depression 18 therein, this recess providing at its forward end a drop-off point 19 for the rollers to permit the metal injecting or casting operation of the pump, and providing toward its rear end an inclined surface 20 leading to the concentric periphery of the cam and with which the rollers cooperate to lift or retract the pump plungers. It will be understood that the cam makes one complete revolution in the direction of the arrow in Figure 1 for each cycle of operation of the machine as usual and that the recess or depression 18 is located at the proper point in the circumference of this cam to cause the metal injecting or casting operation to take place at the proper time.

The arms of the pump levers 6, 7 and 8 which carry the rollers 6^a, 7^a and 8^a, respectively, are so shaped that these rollers are at increasing distances, in the direction of rotation of the cam, from the common pivot or fulcrum point 9 of all of the pump levers. One of the pump levers, for example the lever 7, is provided with stop lugs 7^b which project laterally from its opposite sides and are arranged to engage the under sides of shoulders 6^b and 8^b, respectively, of the pump levers 6 and 8. As the cam rotates in the direction of the arrow, the pump plungers connected to the levers 6 and 8 will be held inactive by the engagement of the stop lugs 7^b beneath the shoulders 6^b and 8^b, respectively, after the release point 19 on the cam passes from beneath their respective rollers 6^a and 8^a and until the release

point 19 passes from beneath the roller 7^a of the pump lever 7, whereupon all of the pump plungers will be released simultaneously for the metal injecting operation.

When the cam rotates sufficiently far to bring the inclined surface 20 thereon into contact with the roller 8^a, the pump lever 8 on which this roller is carried will be rocked about the pivot or fulcrum point 9 to lift its respective plunger, immediately succeeding which the inclined surface 20 of the cam will contact with the roller 6^a on the pump lever 6 and will rock the latter about the pivot 9 to lift the plunger connected to this lever, and upon further rotation of the cam, the inclined surface 20 thereon will contact with the roller 7^a on the pump lever 7 and will rock the latter in a direction to lift or retract the pump plunger connected thereto. The arrangement of the rollers is such that by the time the inclined surface 20 on the cam contacts with the roller 6^a, the plunger connected to the pump lever 8 will be almost completely lifted and the pump spring for the lever 8 will be correspondingly stretched nearly to its full tension so that the resistance offered to the rotation of the cam will be only that produced by a single pump spring. Similarly, by the time the inclined surface 20 on the cam contacts with the roller 7^a on the pump lever 7, the pump plunger attached to the pump lever 6 will be almost completely lifted and its spring will have been brought substantially to full tension. Thus, each of the pump plungers will be lifted or retracted by successive contact of their respective rollers with the inclined portion 20 on the cam in such a manner that the power of only one pump spring at a time must be overcome.

In addition to the successive contacting of the cam with the respective pump rollers to lift the respective pump plungers and reset their tension springs, it is to be noted that each successive roller will swing in an arc which is located further from the common fulcrum point 9 in the direction of the circumference of the cam so that the successive rollers will act through lever arms of increasing lengths, resulting in a reduction of the load exerted by each roller on the cam, and while there are a plurality of rollers operating against the inclined rise in the cam as the latter rotates, the wear on the cam will not be increased in proportion to the number of rollers.

In the embodiment of the invention shown in Figures 3, 4 and 5, only one pump plunger 3^a is employed for the metal pump 2 in the metal pot 1^a, this single plunger operating by its descent to inject metal from the metal pot into the mold in the usual manner, the operating rod 21 for the plunger being connected to one arm of a single pump lever 22 which is pivoted to rock on the pivot pin or fulcrum 9, the controlling cam 16 having the drop-off point 19 leading to the recess or depression 18 and the inclined rise 20 leading from said recess, being like that described in connection with Figures 1 and 2, the pump lever being depressed to actuate the pump plunger on its metal injecting stroke by a tension spring 14^a acting on a rod 15^a which bears on the pump lever. In this embodiment of the invention, a plurality of rollers are provided for distributing the load of the pump spring against the cam, two of such rollers 23 and 24 being shown which are rotatably mounted on a bracket or carriage 25, this carriage being pivoted on the pump lever 22 by the pivot pin 26 so that the carriage may rock relatively to the pump lever in the plane in which

the pump lever swings, this carriage 25 in effect forming the roller carrying arm of the pump lever. The pump lever is provided with stop lugs 27 which project laterally therefrom, and the carriage is provided with stop lugs 28 to engage the stop lugs 27 and thereby limit the swing of the carriage in one direction about its pivot 26. While the rollers 23 and 24 are in engagement with and held against the concentric portion of the cam under the pressure of the pump spring, the carriage 25 will occupy the position shown in Figure 3, the engagement of the stop lugs 27 and 28 preventing the weight of the rollers on the carriage from swinging it in an anti-clockwise direction beyond the position shown in this figure. As the cam rotates in the direction of the arrow (Figure 3), the pump plunger will be sustained in its lifted or retracted position until the release point 19 on the cam passes from beneath the last roller 24, this roller being shown about to be released in Figure 3. After the metal injecting stroke of the plunger has taken place, following the passing of the release point 19 on the cam beyond the rollers, the continued rotation of the cam brings the inclined rise 20 thereon into contact with the first roller 23 and thereby tips the carriage 25 about its pivot 26 into the position shown in Figure 4, immediately following which both rollers 23 and 24 will bear against the inclined rise 20 on the cam during the early stages of lifting or retracting the pump plunger. As soon as the further rotation of the cam brings the first roller 23 onto the concentric portion of the cam, the continued rotation of the cam will cause the carriage 25 to rock about its pivot 26 on the pump lever so that the center of rotation of the second roller 24 will be carried to a point further away from the fulcrum point 9 of the pump lever. Such forced rotation of the carriage 25 will thereby increase the length of the lever arm between the fulcrum 9 and the second roller 24, so that the resistance against rotation of the cam during the last stage of stretching the pump spring will be correspondingly reduced.

4. The invention as applied in either of the embodiments hereinbefore described, has the advantage of distributing the load on the cam while the pump is being retracted in such a way that as the total load reacting on the cam increases, due to the stretching or resetting of the pump actuating spring or springs, there will be at least an equalizing compensation of such load, or the power required to lift such load may actually decrease with the increasing load. At the same time, such distribution of the load on the cam among several supporting rollers will proportionately reduce the amount of wear of the cam and it will be possible to increase the pumping pressure by a considerable amount without undue wear or disturbing the operating efficiency of the machine.

I claim as my invention:

1. A casting pump for typographical machines having at least one metal injecting plunger, and a cam for controlling the operation of the pump, pump actuating means connected to the pump and carrying a plurality of rollers running simultaneously on the cam, and stops operative to hold said actuating means in retracted position and to effect full release of the total available actuating force of said actuating means and thereby start the pumping operation of the pump when the rearmost roller is released by the cam.

2. A casting pump according to claim 1 where-

in said rollers distribute to different portions of said cam the resistance encountered thereby in retracting said pump actuating means.

3. A casting pump according to claim 1 wherein in the pump comprises a plurality of pump plungers, said pump actuating means comprises a plurality of different pump levers on which said rollers are carried, and said rollers run one behind the other on the same cam, and said stops are operative to effect full release of said plurality of pump levers and thereby start the pumping strokes of said plungers when the rearmost roller is released by the cam.

4. A casting pump according to claim 1 wherein in the pump is provided with a single pump plunger, said pump actuating means comprises a spring actuated pump lever having a carriage pivoted thereto for carrying said rollers, and a stop is provided on the pump lever to hold said carriage in a position which causes the cam to operate on a lever arm of increased length during the latter stages of tensioning of the pump lever actuating spring.

5. In a typographical machine having a metal pot provided with a metal injecting pump, and a rotary cam having a depression therein for controlling the operation of the pump, spring operated actuating means connected to the pump and carrying a plurality of rollers simultaneously engaging the cam, one behind the other, and means for preventing operation of the pump actuating means and for effecting full release of the total available actuating force of said actuating means and thereby start the pumping operation of the pump when the rearmost of said rollers reaches the depression in the cam.

6. In a typographical machine having a metal pot provided with a metal injecting pump, and a rotary cam for controlling the operation of the pump, pivoted spring operated actuating means connected to the pump and carrying a plurality of rollers located thereon at different distances from the pivotal center of said actuating means and engageable with the cam successively in the order of their distances from said pivotal center, the roller nearest said pivotal center engaging the cam first.

7. In a typographical machine having a metal pot provided with a metal injecting pump and a rotary cam having a depression therein for controlling the operation of the pump, pivoted spring operated actuating means for the pump carrying a plurality of rollers located at different distances from the pivotal center of the actuating means and engageable and disengageable with respect to the cam successively in the order of their distances from said pivotal center, and means for holding said actuating means from operation until the roller most distant from its pivotal center is released by the depression in the cam.

8. In a typographical machine having a metal pot provided with a metal injecting pump embodying a plurality of plungers, and a rotary cam for controlling the operation of said plungers, actuating means for the pump comprising a plurality of pump levers having a common pivot, one lever being connected to each pump plunger and each lever carrying a roller, and a spring for actuating each pump lever, the rollers of said pump levers being engageable with the cam at different distances from the pivotal center of the pump levers, and the lever carrying the roller most distant from said pivotal center having means for holding the other pump levers against

actuation until the cam releases said most distant roller.

9. In a typographical machine having a metal pot provided with a metal injecting pump embodying a plurality of plungers and a rotary cam for controlling the operation of said plungers, actuating means for the pump comprising a plurality of pump levers having a common pivot, one lever being connected to each pump plunger and each lever carrying a roller, and a spring for actuating each pump lever, the rollers of said pump levers being engageable with the cam at different distances from the pivotal center of the pump levers, and the lever carrying the roller most distant from said pivotal center having stop lugs thereon to engage other of said pump levers and thereby hold them against actuation until the cam releases said most distant roller.

10. In a typographical machine having a metal pot with a metal injecting pump therein, and a rotary cam for controlling the operation of said pump, a pump lever carrying thereon a plurality of rollers simultaneously engaging said cam, and means for preventing the operation of the pump until the cam disengages the last one of said rollers.

11. In a typographical machine, the combination of a metal pot, a pump plunger therein, a spring actuated operating lever therefor, a rotary cam for controlling said lever, and a plurality of rollers carried on said lever and engageable with said cam, said rollers engaging said cam simultaneously at different points during the rotation of said cam to correspondingly distribute the load of the pump spring thereon.

12. In a typographical machine having a metal pot and a metal injecting pump, a rotary cam for controlling said pump, and a pivoted pump lever carrying a plurality of rollers thereon at increasing distances, in the direction of rotation of said cam, from the pivotal point of said lever, said rollers being engageable with the pump retracting portion of said cam successively in the order of their increased distances from the pivotal point of said lever, the roller nearer said pivotal center engaging the cam first.

13. In a typographical machine having a metal pot provided with a metal injecting pump embodying a plunger, and a rotary cam for controlling the operation of said pump plunger, actuating means for the pump comprising a pivoted pump lever connected to said plunger, a spring for actuating said lever, and a member pivoted

on said pump lever and carrying a plurality of rollers located at different distances from the pivotal center of the pump lever and engageable successively by the cam, said member being swingable about its pivot on the pump lever under the action of the cam on said rollers in retracting the pump plunger to increase the distances of said rollers from the pivotal center of the pump lever.

14. In a typographical machine having a metal pot provided with a metal injecting pump embodying a plunger, and a rotary cam having a depression therein for releasing the pump, actuating means for the pump comprising a pivoted pump lever connected to said plunger, a spring for actuating said lever, a member pivoted on said pump lever to swing relatively thereto and carrying a plurality of rollers located at different distances from the pivotal center of the pump lever and engaging said cam one behind the other, and stop means for limiting the swing of said member in one direction relatively to said pump lever to hold the latter in retracted position until the roller most distant from the pivotal center of the pump lever is released by the depression in the cam, said rollers being engageable successively with the cam beyond said depression and operative to swing said member in a direction to increase the distance of the rollers thereon from the pivotal center of the pump lever while the cam is acting on said rollers to retract the pump lever.

15. The combination, with casting mechanism for typographical machines having metal injecting means and retractable actuating means therefor, of control means for said actuating means comprising a single rotatable cam, a plurality of cooperating rollers operatively associated with said actuating means, and means for distributing the load of retracting said actuating means to different portions of said cam.

16. Casting mechanism for typographical machines, which comprises metal injecting means, releasable and retractable actuating means therefor, control means for said actuating means including a single rotatable cam and a plurality of cooperating rollers each operative to assist in retracting said actuating means, and means for causing the full release of said actuating means at a predetermined point in the rotation of said cam.
